UNITED STATES PATENT OFFICE.

STEFANO BOZANO, OF MATTAPAN, ASSIGNOR OF ONE-HALF TO PASQUALINA CALEDONIA, OF BOSTON, MASSACHUSETTS.

PERMUTATION-PADLOCK.

SPECIFICATION forming part of Letters Patent No. 546,969, dated September 24, 1895.

Application filed July 22, 1895. Serial No. 556,677. (No model.)

To all whom it may concern:

Be it known that I, STEFANO BOZANO, a citizen of Italy, and a resident of Mattapan, in the county of Suffolk and State of Massachusetts, have invented new and useful Improvements in Permutation-Locks, of which the following, taken in connection with the accompanying drawings, is a specification.

This invention relates to improvements in permutation-locks of the kind generally termed "letter" or "puzzle" locks, and it is carried out as follows, reference being had to the accompanying drawings, wherein—

Figure 1 represents an outside elevation of the improved lock, shown in a locked position. Fig. 2 represents an interior view of the said lock, also shown in a locked position. Fig. 3 represents a similar interior view showing the lock open. Fig. 4 represents a vertical section on the line 44, shown in Fig. 2. Fig. 5 represents a longitudinal section on the line 55, shown in Fig. 2. Fig. 6 represents a detail perspective view of the slotted guide-tube, in which the bolt is guided. Fig. 7 represents a detail side view of the locking-bolt, and Fig. 8 represents end views of the letter-disks.

Similar letters refer to similar parts wherever they occur on the different parts of the drawings.

A A' represent the front and rear portions of the inclosing shell or case, to which is secured the bottom piece A'' and A³ and top A⁴, as is common in padlocks.

B is the bow, as usual, pivoted at b, and having a hook or locking recess B' in its free end, as shown.

C is a movable end piece that constitutes a portion of the inclosing case, said end piece being pivoted on a pin C', secured to the plates A A', and normally held in the position shown in Figs. 2 and 5 by the influence of the spring D, interposed between the lower portion of the end piece C and a stationary block E, secured to the plate A', and to said block is secured a longitudinally-slotted sleeve F, having on one of its sides a slit f, as fully shown in Fig. 6. Within said sleeve and a perforation in the block E is longitudinally adjustable the bolt G, provided with a series of side projections g g g, as shown in Fig. 7. On the sleeve F is journaled a series of annular disks H H H, having a portion of their peripheries projecting through openings a and a' in the plates A A', as shown. Each of such disks H has on its interior a longitudinal groove h, adapted to receive the corresponding projection g on the longitudinally-movable locking-bolt G, as shown in Figs. 4, 5, and 8. The disks H H H have numbers or letters or other marks on their peripheries, as shown in Figs. 1, 2, and 3, as is common in letter or puzzle locks. When the disks H are all turned to such a position that their longitudinal grooves h are in alignment with the projection g on the bolt G, then the latter may be moved freely toward the left by pressing inward on the lower portion of the movable end piece C, as shown in Fig. 3, and in so doing the left-hand end of the said bolt G comes in contact with a pivoted lever I, that is pivoted at i and provided with a hooked upper end I', as shown in Figs. 2 and 3. Normally the hooked end I' of said lever I is held in locking engagement with the notched end B' of the bow B by the influence of a spring K, as shown in Fig. 2. When the hooked lever I is released from the bow B and swung to the position shown in Fig. 3 by pressure on the end piece C after the disks H H H have been adjusted, the released bow B is automatically swung upward by the influence of a spring L to the position shown in Fig. 3. As soon as the operator relieves the pressure on the end piece C the latter is moved by the spring D to its normal position, (shown in Figs. 2 and 5,) and the lever I and bolt G are moved to their normal positions (shown in said Figs. 2 and 5) by the influence of the spring K, after which the bow B may be locked simply by swinging it to the position shown in Figs. 1 and 2, causing the notch B' on said bow to be interlocked with the spring-pressed hooked lever I, as shown in Fig. 2. The disks H H H are then turned around sufficiently to cause their grooves h to be placed out of alignment with the bolt projections g. The disks H may be marked with numbers or letters, &c., on their circumferences to serve as means for locating them in position for unlocking the bolt, as is common in locks of this kind. In practice I prefer to provide the case-plates A A' with the respective hinged covers M M' for

closing the openings a a' when not manipulating the disks II II II, as shown in Figs. 1 and 4.

Having thus fully described the nature, construction, and operation of my invention, I wish to secure by Letters Patent and claim—

In a permutation lock, in combination, an inclosing case, a pivoted bow B, a spring pressed pivoted end piece C, a stationary slitted sleeve F, a locking bolt G longitudinally adjustable in said sleeve and having side projections g , a series of lettered or numbered disks II journaled on said sleeve and having

internal grooves h and a spring pressed hook lever I adapted to engage with the free end of the bow, substantially as and for the purpose set forth.

In testimony whereof I have signed my name to this specification, in the presence of two subscribing witnesses, on this 17th day of July, A. D. 1895.

STEFANO BOZANO.
